UNITED STATES PATENT OFFICE.

HARRY M. SCHLOSS, OF JERSEY CITY, NEW JERSEY.

ADJUSTABLE SUPPORT FOR WINDOW-SHADES.

1,267,464.

Specification of Letters Patent.

Patented May 28, 1918.

Application filed September 26, 1914. Serial No. 863,597.

To all whom it may concern:

Be it known that I, HARRY MARTIN SCHLOSS, a citizen of the United States, and resident of the city of Jersey City, county 5 of Essex, State of New Jersey, have invented certain new and useful Improvements in Adjustable Supports for Window-Shades, of which the following is a specification.

This device is intended as a further improvement in an art that has been developed 10 to provide a means whereby a window shade hung or attached to a window in an ordinary position may be lowered from that position to any other desirable position upon 15 the window.

By this operation a means is provided whereby light and ventilation may be obtained from the top of the window and at the same time the lower portion or any other 20 portion of the window may be shaded and the light and view excluded therefrom.

In this invention I have attempted to cheapen and simplify the construction and 25 operation of the device and to make other and important improvements in the design and construction that will enable the device to efficiently fulfil every requirement.

The construction and method of operation 30 will be fully set forth as the specification progresses.

The following is what I consider the best means of carrying out this invention, and

The accompanying drawings form a part of this specification, in which:

35 Figure 1 shows in elevation one side of a window fitted with an inside bracket.

Fig. 2 shows the opposite side of another window fitted with an outside bracket.

The remaining figures are on a larger 40 scale.

Fig. 3 shows a companion bracket to that shown in Fig. 1.

Fig. 4 shows a companion bracket to that shown in Fig. 2.

45 Fig. 5 shows a front elevation of one of the pulley brackets used in Fig. 2.

Fig. 6 shows a section through a guide rod and an elevation of one of the sliders, arranged thereon.

50 Fig. 7 shows a modification of an outside bracket.

Fig. 8 shows in perspective one of the tubular cups which retain the lower ends of the rods.

Similar reference numerals indicate like 55 parts in all the figures where they appear.

Referring to the drawings it will be noted that the portion of window casing shown in each drawing is indicated by the reference characters 1 and 2. 1 indicates a casing 60 adapted to receive an inside bracket, and 2 a casing adapted to receive an outside bracket.

These casings may be of ordinary construction and as they need no change for the 65 reception of my device I do not deem it necessary to describe them.

At 3, I indicate what I may term a guide rod. I provide two of these rods for each window securing them parallel to each other, 70 and one to each side of the window casing. These rods may be round solid rods of a diameter sufficient to insure the required rigidity.

The lower end of each rod is received in a 75 bracket member 4 which consists of a tubular cup the edges of which are unjoined but which terminates in points 5 and 6 which assist in retaining the cup in position. An extension formed integral with the cup is 80 bent inward at the lower end of the cup to provide a stop and support for the rod and then downward as indicated at 7, to receive a perforation to accommodate a securing screw 8, which is entered at a convenient point in the casing of the window. 85

The upper end of the rod is received in a pulley bracket but as the pulley brackets for inside and outside fixtures are of different construction I will first describe that shown 90 in connection with Fig. 1.

This bracket as indicated at 9 has formed integrally therewith a plurality of semi-tubular lugs 10 and 11 which engage the upper end of the rod 3. These lugs like the 95 cup of the member 4 do not entirely surround the rod but the inner edge of each is open so that when the rod is secured by the cup 4 and brackets 9 it will rest upon the wood work of the casing of the window. 100

Formed integrally with the bracket 9 I provide a plurality of outwardly projecting

lugs 12 and 13 which receive a pin 14 upon which is rotatably mounted a roller 15 for a purpose that shall appear later.

Each of the pair of rods arranged upon a window such as shown in Fig. 1 are supported in the manner described but it will be noted that although the upper or roller supports are similar in construction when they are arranged upon a window one is in a reversed condition to the other so that the rollers project outward from the rods.

Arranged upon each rod is a sliding member 16 similar in general outline but one is provided with a perforation 17 to receive the pin of a shade roller and the other with a slot to receive the spring end of the roller. Each of these brackets are provided with a plurality of lugs 18 and 19 which may be formed integral with the bracket and through which the guide rod will pass. These lugs do not entirely surround the rod but engage thereon in the manner shown in Fig. 6.

Projecting from the upper edge of each sliding bracket is a stop as shown at 20. These stops insure that the upward movement of the brackets will not be sufficient to allow the shade roller to come in contact with the casing of the window. I also provide a perforation 21 in each bracket into which an operating cord or chain may be engaged.

Projecting inwardly from each of the sliding brackets and formed integral therewith I provide a member, of box section as shown at 22, which has a V shaped slot or key way 23 produced therein and between the opposite brackets and retained in the key-ways or slots is a spreader 24.

The operation of this device may appear obvious from the construction but I will however briefly describe it.

A cord or other flexible member is secured in the perforation 21 of each of the sliding brackets. The cords are then extended upward parallel with the rods upon which the brackets operate and are passed over the pulleys at the top of the rods. The left hand pulley receives one cord, the cord from this pulley continues across the window to join the opposite cord in passing over the right hand pulley. Both are then carried downward and may be joined together to terminate in a single pull cord by which the device may be operated. A pull on the cord will raise the roller and the shade. The cord may then be secured to a convenient cleat.

The operation of the device shown in relation to Fig. 2 is exactly similar to that heretofore described but it will be noted that the pulley brackets 26 extend away from the window and that additional securing lugs

or perforated feet 27 and 28 are provided. I also find it convenient to provide a perforation or hole 29 through which the operating cords may pass.

It will also be noted that the roller supporting brackets are larger and project away from the guide rods. In this construction the guide rods are not secured against the casing, the lower brackets or thimbles may then be complete tubular members with securing lugs and the upper brackets may have slotted portions 30 and 31, which are rolled or shaped to completely surround the rods. The rod engaging lugs of the sliding brackets may be formed from projections 32 and 33 extending inward from the bracket and bent into tubular shapes to engage the rods and the stops 34, may be formed with the uppermost rod engaging lug. I provide perforations for the engagement of the flexible member in the body of the bracket at 35 or 36. It will be understood that the width of the upper stationary bracket and sliding bracket are sufficient to support the shade a proper distance from the casing.

In the earlier figures I have described that outside sliding brackets as formed with solid bodies having short projecting lugs, but it will be noted in Fig. 7 that the area of the bracket proper is decreased in size and that the lugs 40 and 41 are lengthened to project the bracket the proper distance from the casing. In this construction I perforate the upper lug for the reception of the flexible member.

Other modifications may be made within the scope of the appended claims without departing from the principle or sacrificing the advantages of this invention.

Having carefully and fully described my invention what I claim and desire to secure by Letters Patent is:

1. In a shade adjuster comprising a rod, a member adapted to slide upon said rod comprising a shade receiving bracket, a plurality of lugs formed integral with one side of said bracket and adapted to engage said rod, a box shaped portion formed integral with said bracket and projecting transverse to said lugs, said box shaped portion being provided with a V shaped groove and a distending means one end of which is adapted to be received in said groove.

2. In a shade adjuster comprising a rod, a member adapted to slide upon said rod, and means for supporting the upper end of said rod and comprising a plate having a plurality of perforated foot pieces turned at right angles to said plate, a plurality of tubular lugs extending in the direction of said foot pieces and adapted to receive said rod and a plurality of lugs formed integral

with said plate and extending in a direction opposite to said foot pieces, a roller received between said last mentioned lugs and a flexible member passing over said roller and connected to said slideable member for operating said slideable member as and for the purpose set forth.

Signed at New York city, in the county and State of New York this 24 day of September 1914.

H. M. SCHLOSS.
